UNITED STATES PATENT OFFICE.

PATRICK HENRY QUINN, OF CORYDON, PENNSYLVANIA.

RAILWAY-TIE AND RAIL-FASTENING.

SPECIFICATION forming part of Letters Patent No. 739,217, dated September 15, 1903.

Application filed March 16, 1903. Serial No. 147,954. (No model.)

To all whom it may concern:

Be it known that I, PATRICK HENRY QUINN, a citizen of the United States, and a resident of Corydon, in the county of Warren and 5 State of Pennsylvania, have made certain new and useful Improvements in Railway-Ties and Rail-Fastenings, of which the following is a specification.

The object of my invention is to provide an 10 improvement in metallic railway-ties and means for securing rails thereto or to other preferred forms of base-support.

The details of construction, arrangement, and combination of parts are as hereinafter 15 described, reference being had to accompanying drawings, in which—

Figure 1 is a perspective view illustrating my invention. Fig. 2 is a horizontal section on the line 2 2 of Fig. 1. Fig. 3 is a vertical 20 section on the line 3 3 of Fig. 1. Fig. 4 is a detail view illustrating the open slot or notch in the tie. Fig. 5 is a perspective view of the wedge-key or fastener. Fig. 6 is a section on the line 6 6 of Fig. 3.

25 The rail A is constructed in the usual form. The tie B is constructed of metal, preferably rolled steel, and it is made trough-like with two parallel vertical side flanges b. The latter are provided with notches or open slots b', 30 (see Fig. 4,) which are undercut on the outer side to adapt them to receive the flanged wedge-keys C. The latter clamp and secure the rail A to the tie B and upon the wooden base-block D. They are metal bars (see Fig. 35) having the inwardly-bent flange or lip c, Figs. 1 and 3, which overlaps a base-flange a of the rail A, and on the outer side they are provided with two sets of cams or inclined 40 projections c' and c''. Thus the key C is constructed on the outer side of each end portion with a vertical part c', which is inclined inward from one end to the other, and at the lower edge of such incline or cam c' is formed a narrow rib or projection c'', whose upper side 45 is inclined from one end to the other.

The flanges b of the tie B are cut away to receive the base of rail A, and the block D supports the latter so that it does not rest upon the flanges. (See Fig. 1.)

50 In laying the track the ties B are fixed in position with the flanges b upward, and the latter may be flush with the road-bed or not,

as preferred. Then the rails A are laid on the blocks D and ties B and the keys C inserted and driven into place by a hammer, 5 sledge, or maul. It will be seen that in such case the lateral inclines or cams c' engage the inward projections, Fig. 4, of the slots in the tie B, so that the key C is forced against the edge of the rail-base a while the inclines or 60 cams c'' engage the under side of such projections and draw the keys C downward upon the rail-base a. In brief, the effect is to clamp the rail A very firmly to the ties both laterally and vertically. 65

To insure against accidental loosening of the keys C, their inclined ribs c' may be provided with holes (see Figs. 1 and 5) to receive a fastening pin or bolt.

The wooden block D provides a duly elastic rail-support which relieves concussion or jar to the required degree. It may be made of any other duly elastic material. The top of the block D has a transverse groove which receives a metal fastening E, Figs. 2 and 3, the 75 same lying flush in said groove and having upturned ends that engage notches in rail-base a. By this means "crawling" or "creeping" of the rails A is mainly prevented.

It is apparent my improved key or wedge 80 fastening may be applied or used with other forms of base-support than the metal ties described—for example, with wooden ties having the usual form of flanged-head spikes.

By the above-described construction and 85 combination of parts I provide an improvement in ties and rail-fastenings which is distinguished by simplicity, strength, security, durability, and cheapness. The tie has also a certain degree of elasticity, whereby an advantage is attained in wear and easy running 90 of rolling-stock. The bottom of the tie is provided with holes to permit escape of water. The holes enable the tie to take a firmer hold on the earth, which aids in preventing slipping of the tie endwise. The bur or rough edge formed in punching the holes is a further aid to this result.

Having thus described my invention, what I claim as new, and desire to secure by Letters 100 Patent, is—

1. The combination, with a flanged metallic rail, and a tie having vertical flanges provided with undercut, open slots, of a fasten-

ing consisting of a flanged bar having a lateral incline and a horizontal incline, which, when the bar is forced into place, act as cams upon the lateral and under sides of said slots, 5 as and for the purpose specified.

2. The combination, with rails and a base support therefor having metal parts which project inward and above the body of said support, of the fastening comprising a flanged bar 10 having on its outer side two inclines adapted to apply lateral and downward pressure on the bar, substantially as specified.

3. The combination, with the flanged rail and a tie having undercut, open slots, of the 15 fastening - key having a lateral projection whose upper side is inclined downward from the outer to the inner end, as shown and described.

4. The combination, with a flanged rail and ties having parallel vertical flanges each provided with undercut portions, of the flanged key-fastenings having two adjacent inclines at each end, one being inclined inward and the other downward, as and for the purpose described. 20

5. The combination, with the flanged and notched rail and trough-like tie, of a block arranged in such tie and having a transverse groove in its top portion, and a locking device laid in said groove and having upturned ends 25 that engage the rail as and for the purpose specified.
